UNITED STATES PATENT OFFICE.

WALTER S. ADAMS, OF PHILADELPHIA, PENNSYLVANIA, ASSIGNOR TO
JOHN A. BRILL, OF SAME PLACE.

DESIGN FOR A SUSPENSION-LINK FOR CAR-TRUCKS.

SPECIFICATION forming part of Design No. 32,034; dated December 26, 1899.

Application filed November 16, 1899. Serial No. 737,239. Term of patent 14 years.

To all whom it may concern:

Be it known that I, WALTER S. ADAMS, a citizen of the United States, residing in the city and county of Philadelphia, State of Pennsylvania, have invented and produced a new and original Design for a Suspension-Link for Car-Trucks, of which the following is a specification.

My invention relates to a new and original design for an article of manufacture—namely, a suspension-link for use in car-trucks; and it consists in the shape or configuration of the same, substantially as shown in the accompanying drawings, in which—

Figure 1 is a side elevation, and Fig. 2 an edge view.

The link comprises, as viewed from the side, a lower and substantially rectangular section or part 1, comprising the upright bars 2, the cross-bar 3, the ends of the bars 2 being in-turned and curved, as at 4, and the upper

section 5, comprising the bar 6, extending upwardly from the cross-bar 3 from between the ends of and inclined slightly from the plane of the cross-bar, the upper end of the bar 6 terminating in a bill or hook 7.

By reference to the drawings it will be noted that all of the bar parts of the link are rectangular in cross-section and that the sides of the bars 2, 3, and 6 are flush with each other. 30

Having described my invention, I claim—

The design for a suspension-link for a car-truck, substantially as herein shown and described.

Signed at the city and county of Philadelphia, State of Pennsylvania, this 2d day of November, 1899. 35

WALTER S. ADAMS.
